UNITED STATES PATENT OFFICE.

ADOLF SCHOEN, OF NEW YORK, N. Y.

HEEL-BREASTING MACHINE.

Application filed September 24, 1921. Serial No. 502,347.

To all whom it may concern:

Be it known that I, ADOLF SCHOEN, a citizen of the United States, and a resident of the city of New York, borough of the Bronx, in the county of Bronx and State of New York, have invented a new and Improved Heel-Breasting Machine, of which the following is a full, clear, and exact description.

10 This invention relates to shoe machinery and particularly to an improved machine for trimming the front of heels and has for an object to provide a construction wherein the unfinished heels may be fed into the machine and automatically cut at the proper place.

15 Another object of the invention is to provide a machine for cutting heel fronts to the desired shape, the arrangement being such that the heels are manually placed in the machine at one point and automatically moved to the cutter and then cut without any further consideration by the operator.

20 A still further object of the invention is to provide a cutter or trimming machine for cutting the fronts of heels of foot wear, the construction including a rotatable platform with holders for heels positioned on the platform to bring the heels in operative position adjacent the cutter so that as the 25 cutter moves the heels will be successively cut.

30 A still further object is to provide a heel cutting machine in which the heels may be fed in at a high rate of speed or at a low rate 35 of speed according to the speed of the machine, the construction being such that the failure to feed blank heels to the machine will not injure the machine.

35 In the accompanying drawings—

40 Figure 1 is a top plan view with one edge broken away showing one embodiment of the invention.

45 Figure 2 is a side view of the machine shown in Figure 1.

Figure 3 is a sectional view through Figure 4 approximately on line 3—3.

Figure 4 is a sectional view through Figure 1 approximately on line 4—4.

50 Referring to the accompanying drawings by numeral, 1 indicates a foundation of any desired kind which supports the various posts 2, 3 and 4, which posts support the driving shaft 5 in suitable journal boxes. An upstanding bracket 6 is also carried by 55 the base 1 and acts as a support for the turntable 7 and certain other parts. Suitable

standards 8 and 9 are connected to the base 1 and act as supports for an arc-shaped plate 10 which is formed with rounded cam ends 11 and 12 and a horizontal section 13. This 60 plate or cam member acts as means for receiving the roller 14 and elevating said roller to a certain place and holding the same elevated during the travel of the turntable 7 for a short distance. An upstanding bracket 65 15 acts as a support and guide for the sliding head 16 which is arranged in a suitable dove-tail in the bracket 15 and carries a cutter or knife 17 held in place by a suitable locking screw 18. Preferably, the knife 17 is 70 provided with a slot so that a vertical adjustment thereof may be secured at any time. The sliding head 16 is provided with an extension 19 to which one end of the link 20 is pivotally connected by a screw 21, the opposite end of said link being pivotally connected to one end of the crank 22 by a pin 23. The opposite end of the crank 22 is connected to the shaft 5 so that when said shaft rotates, knife 17 will be reciprocated 75 in a vertical direction.

80 In the particular construction shown in the drawing, one revolution of the shaft 5 will rotate the table 7 one quarter of a revolution and will cause the knife 17 to form one complete back and forth movement. In using the machine it is intended that the unfinished heel shall be placed on the table 7 and moved around to a position beneath the knife 17, which knife cuts the front 85 thereof so that the heel will present the proper appearance. In order to carry out this intention, the table 7 is rigidly connected with a central shaft 24 (Fig. 4) and said shaft extends through the turned over 90 end 25 of the bracket 6. Secured to the lower end of the shaft 24 is a notched wheel 26 (commonly known as a Maltese cross) co-acting with the roller 27 and the arm 28 for forming a Geneva movement for rotating the table 7. In the drawing only four notches are provided in the cross but if a greater number of stops is desired for table 7, a corresponding number of notches must 95 be provided. The arm 28 for operating the wheel or cross 26 is loosely mounted on a short shaft 29 carried by the post 3 and on which the bevel gear 30 freely rotates, said bevel gear being rigidly secured to arm 28 and continually in mesh with the bevel gear 31 keyed or otherwise rigidly secured to the shaft 5. By this construction and arrange- 100 105 110

ment, whenever the shaft 5 rotates one revolution, the notched wheel or cross 26 will rotate one quarter of a revolution and acting through the shaft 24 will rotate the table 7 5 a quarter of a revolution.

In order to permit the knife 17 to properly cut the heel, the table must be stopped at the proper point for a short time to permit the knife to operate. In order to accomplish this and to prevent too greater movement of the table under the action of momentum, a notched lug 32 is provided on the bottom of the table 7 for each of the notches of the notched wheel 26. A lever 33 is 10 pivotally mounted at 34 on the bracket 6 and has one end 35 positioned to move into the notched lug 32 at the proper time while the opposite end is formed with a hook or abutment 36 co-acting with the cam 37 rigidly 15 secured to the shaft 5. A spring 38 tends to normally hold the lever 33 so that end 35 will remain in the notched lug 32.

During the operation of the machine, the cam 37 moves in the direction of the arrow 25 shown in Figure 4 and, consequently, at the proper time the inclined face 39 engages the hook 36 and raises the same against the action of spring 38. This will cause the end 35 to move out of the lug 32. The parts are 30 so set that this occurs just as the wheel 27 of arm 28 is entering one of the notches 26' of the notched wheel 26. During the quarterly turn of the table caused by the movement of arm 28 as it shifts the wheel 26, end 35 of lever 33 is maintained in an inoperative position as the hook 36 is still riding over the cam 37. At the moment that the table 7 has reached the proper position, hook 36 will snap over the end 40 of cam 37 35 and at the same time the end 35 of lever 33 will move into the notched lug 32 that has been brought to the proper point. In this way, the end 35 quickly moves into the 40 respective notched lugs 32 as they are brought to the proper position, whereupon the table 7 will be locked in a stationary 45 position and held until after the knife 17 has performed its operation. At the same time that the knife performs its operation, the operator may feed or place a new heel 50 in position on the table as hereinafter fully described.

It will be seen that by continuously rotating the shaft 5 by any suitable power, the 55 knife 17 will be continually moving up and down while the table 7 will intermittently move one quarter of a revolution at a time and will then stand still for a short time during the cutting operation. In the drawing 60 the table turns one quarter of a revolution at each movement but if desired a greater or less movement could be provided according to the number of notches 26' and the way the other parts are positioned. As 65 shown in Figure 1, there are four duplicated

sets of mechanism of identical construction and identical operation, there being one set for each of the notches 26' in the wheel 26. For the convenience of description the point marked "A" in Figure 1 will be known as 70 the feeding station and the point marked "B" as the cutting station.

As the machine operates a workman places an unfinished heel on the plate 41 and as soon as the table 7 has moved sufficiently 75 over the wheel 14 to move off of the cam member 13, the clamping shoe 42 will move downwardly under the action of spring 43 and press the unfinished heel against the plate 41 which may be fiber or some other 80 slightly yielding material. At the same time that the shoe 42 moves downwardly for pressing the heel against the plate 41, side 85 shoes 44 and 45 will move laterally for centering and clamping the heel against lateral shifting movement while a stationary or fixed rear brace 46 prevents any rearward movement. By the time that the table 7 has moved a quarter of a revolution, the heel is 90 rigidly clamped in place and the next set of mechanism has moved to station A from station B. The finished or cut heel is released from the shoes 42, 44 and 45 as it approaches station A and may be quickly removed by the operator and an unfinished 95 heel substituted, which unfinished heel will be gripped as above stated when the table 7 moves a sufficient distance for roller 14 to move off of the cam member 13. The shoe 42 is preferably provided with a threaded 100 stem 42' screwed into the head or enlargement 47 of an arm 48, which arm extends through a suitable aperture 49 in the table 7 and which is provided with a bifurcation 105 for accommodating the roller 14. Preferably, a locking nut 42'' is used for locking the threaded shank or shaft 42' against accidental shifting. The arm 48 and roller 14 are held properly in place by a suitable guide 110 rod 50 extending upwardly through the table 7 and around which the spring 43 is positioned. By the action of spring 43, shoe 42 quickly clamps the unfinished heel on plate 115 41 while a different mechanism is provided for operating the shoes 44 and 45. Each of these shoes is provided with a shank 51 on which is pivotally mounted a square block 52 fitting into a rectangular notch 52' formed in the respective arms 53 and 54, which arms 120 merge together and form an inwardly extending shank 55 in which a slot 56 is formed, which slot permits the lug 57 to project therein and act as a guide for the arms 53 and 54. A retaining plate 58 is held 125 in place on lug 57 by suitable screws 59. A hook 60 is connected or formed integral with the shank 55 and is adapted to receive one end of a spring 61, the opposite end being 130 connected with a centrally positioned post

62. In order that the arms 53 and 54 may move radially towards the center for shifting the shoes 14 and 15 toward each other as shown at the bottom of Figure 1, a depending lug 63 (Fig. 4) is provided on the shank 55 and carries a pin or shaft 64 on which a roller 65 is mounted. The roller 65 is adapted to engage the cam 66 rigidly secured to the bracket 6 by screws or some other desirable way. As any particular set of mechanism moves from the cutting position at station B, the roller 65 thereof will engage cam 66 about the same time that the roller 14 engages the cam member 13 so that the arms 53 and 54 will be gradually moved radially outwardly at the same time that the shoe 42 is moved vertically whereby the heel which has been cut will be released. As the parts move from station A toward the left 20 in Figure 1, a reverse action will take place as the respective rollers 14 and 65 move off of their cam members whereupon the respective springs 43 and 61 will act to produce the desired clamping action.

25 In using the machine, heels which have been properly made and trimmed on the sides and the rear are inserted so that the front will be cut off at the desired angle in order to present the desired appearance. 30 When the cut heel has been discharged from the machine, it is finished and ready for use. During the cutting operation of the knife 17, suitable pressure is used and in order to prevent the deflecting of the table 7 at that 35 point, a supporting bracket 68 is provided as shown in Figure 2, which bracket is preferably provided with a roller 67.

What I claim is:—

40 1. A heel cutting machine comprising a turntable, a plurality of sets of mechanism for clamping heels on said table, automatically actuated means for bringing said clamping sets to an unclamped position for removing the cut heels and supplying new uncut heels, 45 a knife arranged adjacent said table for severing the heels as they pass, means for stopping the table as each heel comes opposite said knife, and a single drive shaft for operating the knife and turntable in time relation.

50 2. A heel cutting machine of the character described comprising a table, a plurality of clamping devices arranged on said table, a Geneva movement for rotating said table, 55 a knife arranged adjacent the table, means for operating the knife so as to cut a heel carried by one of the clamping means while the same is held stationary, and means including a pair of cams for automatically releasing the clamping means as they approach a given point whereby the cut heel may be removed and an uncut heel substituted.

3. A heel cutting machine of the character described comprising a rotatable table, a plurality of clamping means arranged on the table for clamping heels, a Geneva movement for rotating said table, a power shaft, bevel gears for operating the Geneva movement, a cam carried by said power shaft, a lug carried by said table for each of the clamps arranged thereon, a pivotally mounted lever co-acting with said cam and with the lugs for locking the table each time the same stops, and cutting means for cutting the heels carried by the clamps as they move to a certain point.

4. In a heel cutting machine of the character described a turntable provided with a plurality of spaced notched lugs, a pivotally mounted lever adapted to move into said lugs at different times for locking the turntable against movement, said lever being formed with a hook end, a rotatable cam for operating said lever so as to cause the lever to move into one of the notched lugs as the turntable reaches certain points in its revolution, and means for rotating continuously said cam.

5. In a heel cutting machine of the character described a turntable for carrying heels, a plurality of clamps arranged on said turntable, each of said clamps having a pair of horizontally moving clamping feet and a vertically moving clamping foot, and means for simultaneously operating said feet so as to grip and release a heel.

6. In a heel cutting machine of the character described a rotatable table, a plurality of heel clamps arranged on said table and means for moving the heel clamps to a clamped and an unclamped position, said means including a reciprocating arm for part of the clamp and a reciprocating forked member for the other part of the clamp and independent cams for said arm and the forked member for moving the same to an unclamped position, and a spring for each of said arms and said forked member for moving the same to a clamped position.

7. In a heel cutting machine a movable member, a clamping device arranged on said movable member and a cutter for cutting the heel carried by the clamping device, said clamping device comprising a vertically movable clamp, a pair of horizontally movable shoes having rotatable bearing members at the ends, a forked member having diagonally arranged notches carrying said bearing members, means for moving said forked member in one direction for moving the clamping device to an unclamped position, and means for moving the forked member in the opposite direction for moving the clamping device to a clamped position.

ADOLF SCHOEN.
